UNITED STATES PATENT OFFICE.

RAGNAR SOHLMAN, HENRIK NORDENFELT, AND HUGO MORÉN, OF BOFORS, SWEDEN.

FUSE FOR HIGH-EXPLOSIVE SHELLS.

1,016,373.

Specification of Letters Patent.

Patented Feb. 6, 1912.

Application filed September 1, 1910. Serial No. 580,091.

To all whom it may concern:

Be it known that we, RAGNAR SOHLMAN, managing director, HENRIK NORDENFELT, assistant director, and HUGO MORÉN, engineer, subjects of Sweden, residing at Bofors, Sweden, have invented new and useful Improvements in Fuses for High-Explosive Shells, of which the following is a specification.

10 The present invention relates to a new and improved safety device adapted to prevent the occurrence of premature explosions of high explosive shells.

The modern high explosives used for 15 armor-piercing shells and common shells (such as trinitrotoluol or similar nitro compounds), require, as is well known, a very powerful percussive shock in order to develop their full explosive effect. Such shock 20 is usually imparted to the bursting charge by a large detonator, which detonates a charge of moderately compressed picric acid, trinitrotoluol, or the like. The use of such large detonators, which must be composed 25 at least in part of a comparatively sensitive fulminate mixture, is, however, accompanied by a certain element of danger, as the detonator may in some cases owing to defects in manufacture or other unforeseen circumstances 30 explode on the discharge of the shell from or while within the gun, thus causing a premature explosion. To avoid the danger resulting from such accidents some fuses for high explosive shells have the percussion 35 cap placed in a specially strong chamber separate from the detonator of the fuse in such a way that a premature explosion of the percussion cap cannot be communicated to said detonator. The percussion cap is brought 40 into its final position by the impact on striking against the object aimed at, or in some cases by the rotation of the projectile, or by the expansion of a compressed spring (in point or head fuses) carrying the detonator 45 of the fuse in a position near to the percussion cap, where it may be exploded by the firing of the latter. These devices have however various drawbacks; this is especially 50 true in connection with the use of compressed springs as hitherto practiced for the purpose of effecting the said movement of the detonator, these being very unsatisfactory and unreliable. A spring resting in a compressed state for years gradually loses 55 its elasticity and may not be relied upon to expand with its original force; on the other hand, no satisfactory device of this kind

has been proposed for base fuses, where the problem of causing the fuse to become operative by the discharge of the shell is somewhat different and in some respects more difficult than in connection with point or head fuses.

The present invention consists in principle in the employment of a movable member in the shape of a rod or a ring, which is held in position by a disk or the like with protruding arms, or by a pin, or in some other suitable way, so that the inertia of the movable member, when the projectile is suddenly started in motion by the discharge of the gun, is sufficient to overcome the resistance of the arms of the ring aforesaid, or to shear the pin holding it, and thereupon to cause the compression of a spring placed in the rear of the movable member; as long as the acceleration of the shell continues, that is, as long as the shell moves in the bore of the gun, and some short distance in front of the muzzle, the said spring is kept under compression by the inertia of the movable member; but when the acceleration stops the spring returns to its initial position. The return movement of the spring is utilized to bring the primer into such position relatively to the detonator of the fuse that it may explode the latter on being fired.

In the accompanying drawing Figures 1 to 6 show three different embodiments of the invention in longitudinal section: Figs. 1, 3 and 5 showing the shells in inoperative position and Figs. 2, 4 and 6 showing them in operative position.

Referring to Figs. 1 and 2, *a* is the movable member, which is held in position by a ring or disk *b* having four arms resting against the edge of the bore of the recess *c* in the primer carrier *e*. The other end of the said carrier contains the primer charge *f*. On discharge of the gun, the inertia of the member *a* causes considerable pressure to be exerted on the disk *b* so that its arms yield and allow the spindle of the member *a* to enter into the recess in the carrier *e*. In this movement the member *a* compresses the helical spring *h*. When the acceleration of the shot ceases, the spring *h* returns to its normal position carrying with it the member *a*, as the arms of the disk *b* when forced into the recess of the carrier *e* hold the two parts *a* and *e* firmly together, and the movement of the member *a* being transmitted to the primer carrier, the parts occupy the position shown in Fig. 2. On striking against

the object aimed at the flame from the percussion cap *i* ignites the primer *f* the explosion of which fires the detonator *m*; an accidental explosion of the primer *f* when in 5 the position shown in Fig. 1, is not communicated to the detonator *m* and only causes the outer casing of the fuse to bulge out around the primer chamber. This casing must however be made of such material 10 and such dimensions that it may resist the accidental explosion of the primer without bursting.

In Figs. 3 and 4, the movable member *a* is of annular formation and is held in position by a four armed disk *b* which arms are compressed by the pressure due to the inertia of the ring, when the projectile is started in motion. In moving backward the ring *a* compresses the helical spring *h* 20 and finally forces the arms of a second disk *d* to contract within the bore of the ring *a*. The disk *d* is thus connected with the ring *a* and when the latter again moves forward, owing to the return movement of the spring *h*, the disk *d* and the primer *f* are also carried forward into the firing position.

In Figs. 5 and 6 the ring *a* is held in its initial position by the four arms of a disk *b* protruding into the bottom part of the 30 primer carrier. The operation of this arrangement, as shown by Fig. 6, is similar to the preceding modification.

In some fuses the force of the primer when exploded in due course by the detonation of a percussion cap *k* and of an intermediate primer *l* of suitable power, may however be greater than if the primer explodes directly by the concussion on the 35 firing of the round. It may thus present some difficulties to produce a casing strong enough to resist, with absolute impossibility of cracking, the detonation due to a premature ignition of the percussion cap *k* and communicated in regular course through the 40 intermediate primer *l* to the large primer *f*, whereas the casing may be quite strong enough to resist the less powerful detonation of the primer *f* due to direct percussion (in connection with a faulty manufacture 45 of the primer). To avoid this difficulty we have combined with the arrangement for causing the fuse to become operative, as hereinbefore described, a second safety device, operated by the same movable parts, 50 and acting in such a way that communication of the flame from the percussion cap *k* is shut off until the acceleration of the projectile ceases, that is, until the projectile 55 has left the gun. This safety arrangement 60 may be varied in different ways. Figs. 3, 4 and 5, 6 show two modifications thereof. In Figs. 3 and 4 the communication of flame from the cap *k* is normally shut off by a

slide valve *n* which is held in position by a pin *o* or the like connected with the disk *d*. 65 When the disk *d* is carried forward as hereinbefore described by the return movement of the spring *h* the said slide valve *n* is released and is forced outward by the centrifugal force due to the rotation of the 70 projectile, thus leaving the communication of flame open from the cap *k*. In Figs. 5 and 6, the casing of the primer *f* is provided with a lid *r*, carrying a tubular prolongation *v* which fits into a recess *z* in the body 75 of the fuse.

The acceleration of the projectile, when moving in the bore of the gun, causes the detonator to exert a certain pressure on the lid *r* and tube *v* and thus insures a perfect 80 tight fit of the latter in the recess *z*. If the cap *k* and intermediate primer *l* are accidentally fired in this position, the detonation is therefore not communicated to the large primer *f*.

Having now particularly described the nature of our invention and the manner of its operation, what we claim is:

1. In percussion base fuses for shells, the combination with a fixed detonator charge 90 and a movable primer charge which is normally positioned in a strong chamber behind and separate from the detonator charge, of an inertia operated member and a spring positioned behind the same adapted to be compressed by the movement of said member during the acceleration of the projectile, said movement of said member operatively connecting it with the movable primer charge, whereby the latter will be 100 moved forward in active position by said spring.

2. In percussion base fuses for shells, the combination with a fixed detonator charge and a movable primer charge which is normally positioned in a strong chamber behind and separate from the detonator charge, of an inertia operated member adapted to be operatively connected to the movable primer charge during the acceleration of the projectile, a spring positioned behind said member, and a safety device normally shutting off communication between the percussion cap and the primer charge, said safety device being released by 110 the return movement of said spring.

In testimony whereof we have signed our names to this specification in the presence of two subscribing witnesses.
